DESIGN FOR A COMB OR THE LIKE

Bernard Ulvad, Leominster, Mass., assignor to
Fosgood Corporation, Leominster, Mass., a corporation of Massachusetts

Application December 24, 1947, Serial No. 143,315

Term of patent 14 years

(Cl. D86—8)

To all whom it may concern:

Be it known that I, Bernard Ulvad, a citizen of the United States, residing at Leominster, in the county of Worcester, State of Massachusetts, have invented a new, original, and ornamental Design for a Comb or the like, of which the following is a specification, reference being had to the accompanying drawings, forming part thereof, in which:

Fig. 2 is a top plan view of the comb; and,

Fig. 3 is an end view thereof.

The essential features of my design reside in the parts shown in full lines.

I claim:

The ornamental design for a comb or the like, substantially as shown and described.

BERNARD ULVAD.
